UNITED STATES PATENT OFFICE.

ANDREW S. CAIRNCROSS, OF ST. PAUL, MINNESOTA, ASSIGNOR TO SHERMAN T. WOLFE, OF ST. PAUL, MINNESOTA.

PEAT-DRYING APPARATUS.

1,036,072.

Specification of Letters Patent. Patented Aug. 20, 1912.

Application filed April 7, 1911. Serial No. 619,520.

To all whom it may concern:

Be it known that I, ANDREW S. CAIRNCROSS, a citizen of the United States, residing at St. Paul, in the county of Ramsey 5 and State of Minnesota, have invented certain new and useful Improvements in Peat-Drying Apparatus, of which the following is a specification.

My invention relates to improvements in 10 drying apparatus designed particularly for drying peat, and consists in the features of construction and combination hereinafter described and claimed.

In the accompanying drawings forming 15 part of this specification Figure 1 is a longitudinal vertical section of my improved invention partly broken away; Fig. 2 is a similar view of the outlet end of the apparatus; Fig. 3 is a top view of the feed chamber of 20 the apparatus; Fig. 4 is a perspective view of the beating mechanism arranged inside the feed chamber, partly broken away; Fig. 5 is a section on line $x-x$ of Fig. 1; Fig. 6 is a section on line $y-y$ of Fig. 1; Fig. 7 is 25 a longitudinal section of a portion of steam pipe forming part of my invention; Fig. 8 is a perspective view, broken away, of the outlet conveyer of my invention; and Fig. 9 is a perspective view, broken away, of the 30 outlet end of the drying chamber.

Referring to the drawings A represents a vertical feed chamber. Vertically disposed within the feed chamber is a shaft 2 journaled at its upper end in skeleton frame-work 3 across the top of the hopper, and at 35 its lower end in the frame-work 4 supported above the boiler 5. The shaft 2 carries a plurality of beater arms 6, which extend outwardly between the intermeshing arms 7 projected inwardly from the side wall of 40 the feed chamber. The arms 6 and 7 are preferably oppositely inclined as shown in Fig. 4 in order better to treat the material as it passes through the chamber. A tube 8 45 leads from the lower end of a drying chamber 9. Within the tube or conduit 8 is journaled a screw conveyer 10, which carries at its feed chamber end a plurality of beater arms 11. The conveyer shaft at the outlet 50 end of the conduit also carries a plurality of beater arms 12 which work between inwardly extending arms 13 carried by the wall of the tube. The drying chamber 9 55 is rotatable within the inclosing casing 14 and rests upon the anti-friction rollers 15.

Within the drying chamber is a spiral steam pipe 16 connected with the boiler outside the inlet end of the drying chamber by means of a pipe 17. The opposite end of the steam coil 16 is connected with a discharge pipe 17² which may lead back to the boiler, as indicated in Fig. 1. Carried within the drying chamber by the steam coil are a plurality of blades 18 which serve to throw the peat away from the sides of the chamber toward the center thereof and feed the same forward as the chamber and coil revolves. The discharge end of the drying chamber opens into a hopper 19 from which leads the discharge conduit 20. The discharge conduit 20 contains a screw conveyer 21, the shaft of which supports at the outer end of the conduit a plurality of beater arms 22 which work between inwardly extending arms 23 carried by the conduit.

As shown in Fig. 1, the combustion chamber of the boiler furnace leads into the casing 14 underneath the drying chamber, whereby the products of combustion pass under the drying chamber and into the open 80 discharge end thereof, whence they pass through the drying chamber and outward through the discharge pipe 24 to assist drying the material.

The different operative parts are operated 85 as follows: Supported upon the outer end of the shaft of the screw conveyer 10 is a drive pulley 25 adapted to be driven from a suitable source of power. The shaft of the screw conveyer 10 outside of said drive pulley 90 has bevel gear and shaft connection 26 with the lower end of the shaft 2 journaled within the feed chamber. Centrally mounted upon the outer end of the supporting shaft of the screw conveyer 21 is a pulley 95 27 adapted to be driven from a suitable source of power. The shaft of the screw conveyer 21 carries at its inner end a pinion 28 intermeshing with the pinion 29, which in turn meshes with a toothed ring 30 100 surrounding the drying chamber, whereby the drying chamber will be rotated as the screw conveyer 21 is rotated. In Fig. 7 is shown the connection between the steam pipe 17 and the spiral steam coil pipe 16. It will 105 be seen that the pipe 17 extends into the end of the pipe 16, and a steam tight joint is formed by means of the gland 31 and sleeve 32.

When the actuating parts are in opera- 110

tion the material to be dried is fed into the top of the feed chamber A, and in passing through this chamber is beaten up or macerated by the coöperating beater arms 6 and 7. From the feed chamber the peat is carried by the screw conveyer 10 to the drying chamber, and in its passage is further beaten up in the conveyer by means of the beater arms 11 and the coöperating beater arms 12 and 13. The material is conveyed through the drying chamber by means of the steam coil 16 and the blades 18 coöperating with the rotatable drying chamber, and in its passage is thoroughly dried by means of the steam heated coil 16, and the hot products of combustion passing from the boiler furnace through the drying chamber. From the drying chamber the material passes into the hopper 19, to the discharge pipe 20 through which it is carried by means of the screw conveyer 21, working therein. In passing through the pipe 20 the dried material is further beaten up by the coöperating beater arms 22 and 23.

25 I claim as my invention:

1. A drying apparatus of the class described, comprising a feed chamber, beating apparatus arranged within said feed chamber, means for actuating said beating apparatus, a boiler and furnace, a rotatably supported drying chamber connected with the chamber of said furnace, a screw conveyer connecting said feed chamber and drying chamber, a steam coil within said drying chamber, a connection between said steam coil and boiler, and conveyer blades supported by said steam coil.

2. A drying apparatus of the class described, comprising a feed chamber, beating apparatus arranged within said feed chamber, means for actuating said beating apparatus, a boiler and furnace, a rotatably supported drying chamber connected with the combustion chamber of said furnace, a screw conveyer connecting said feed chamber and drying chamber, a steam coil within said drying chamber, a connection between said steam coil and boiler, conveyer blades supported by said steam coil, and a discharge screw conveyer arranged in connec-

tion with the outlet end of said drying chamber.

3. A drying apparatus of the class described comprising a drying chamber, means for feeding material to be dried to said chamber, a spiral steam coil arranged around the interior wall of said drying chamber, and means for rotating said coil and chamber.

4. A drying apparatus of the class described comprising a drying chamber, a spiral steam coil arranged around the interior wall of said chamber, means for feeding material to be dried to said chamber, means for beating up said material, and means for rotating said chamber and coil.

5. In drying apparatus of the class described comprising a drying chamber, a boiler and furnace, the combustion chamber of said furnace opening into one end of said drying chamber, a steam coil within said drying chamber, a connection between said steam coil and boiler, and means for rotating said steam coil and chamber.

6. A drying apparatus of the class described comprising a drying chamber, means for feeding the material to be dried thereto, a steam coil extending spirally around the interior of said chamber and means for rotating said coil and chamber.

7. A drying apparatus of the class described comprising an outer chamber, a drying chamber rotatably supported within said outer chamber, means for feeding material to said drying chamber, heating means arranged in coöperation with said feeding means, a boiler and furnace, the combustion chamber of said furnace being connected through said outer chamber with the interior of said drying chamber, a steam coil arranged within said drying chamber and connected with said boiler and discharge mechanism leading from said outer chamber.

In testimony whereof I affix my signature in presence of two witnesses.

ANDREW S. CAIRNCROSS.
